TEETH CLEANING APPARATUS

James R. Dougherty, 5913 NW. 82nd Circle,
Oklahoma City, Okla. 73132

Filed Mar. 9, 1971, Ser. No. 122,652

Term of patent 3½ years

Int. Cl. D24—03

U.S. Cl. D24—1

FIG. 1 is an elevational view of one side of a teeth cleaning apparatus showing my new design;

FIG. 2 is a top plan view of the teeth cleaning apparatus of FIG. 1;

FIG. 3 is an elevational view of the other side of the teeth cleaning apparatus of FIG. 1;

FIG. 4 is a bottom plan view of the teeth cleaning apparatus of FIG. 1;

FIG. 5 is an elevational view of one end of the teeth cleaning apparatus of FIG. 1, and

FIG. 6 is an elevational view of the other end of the teeth cleaning apparatus of FIG. 1.

I claim:

The ornamental design for teeth cleaning apparatus, substantially as shown.
